DESIGN FOR AN EYESHIELD OR THE LIKE

John A. English, Trenton, N. J.

Application May 12, 1939, Serial No. 84,940

Term of patent 14 years

To all whom it may concern:

Be it known that I, John A. English, a citizen of the United States, residing at Trenton, in the county of Mercer and State of New Jersey, have invented a new, original, and ornamental Design for an Eyeshield or the Like, of which the following is a specification, reference being had to the accompanying drawing, forming a part thereof.

Fig. 1 is a front elevation of an eyeshield or the like embodying my invention.

Fig. 2 is a top plan view of the eyeshield or the like illustrated in Fig. 1.

Fig. 3 is an end view of the eyeshield or the like as seen from the right of Fig. 1, and

Fig. 4 is a perspective view of the eyeshield or the like illustrated in Fig. 1 as it appears in use.

I claim:

The ornamental design for an eyeshield or the like, substantially as shown.

JOHN A. ENGLISH.
